UNITED STATES PATENT OFFICE.

HARLAN P. WELLMAN, OF ASHLAND, KENTUCKY.

PORTABLE ELECTRIC HAND-LAMP.

982,651.

Specification of Letters Patent. Patented Jan. 24, 1911.

Application filed May 19, 1910. Serial No. 562,226.

To all whom it may concern:

Be it known that I, HARLAN P. WELLMAN, of Ashland, in the county of Boyd and State of Kentucky, have invented certain new and useful Improvements in Portable Electric Hand-Lamps; and I do hereby declare the following to be a full, clear, and exact description of the invention, such as will enable others skilled in the art to which it applies to make and use the same.

It is well known that in the use of portable electric hand lamps the connecting cords are subjected to the greatest wear, and have to be frequently replaced.

The primary object of my invention is to provide means for protecting the connecting cord and plug when the lamp is not in use; and a further object is to accomplish this end by means which will be inexpensive and not disfigure the appearance of the lamp.

The invention will be hereinafter fully set forth and particularly pointed out in the claims.

In the accompanying drawings, Figure 1 is an elevation of the lamp showing the parts in position when the lamp is not in use, portions being broken away. Fig. 2 is an elevation showing the lamp with the cord and connecting plug removed and ready for use. Fig. 3 is a sectional elevation with the cord inclosing cover removed. Fig. 4 is a similar view showing the plug fitted in sockets and the cord partly unwound. Fig. 5 is a view of the cover detached. Figs. 6 and 7 show slight modifications, and likewise Figs. 8 and 9. Fig. 10 is a section on line 10—10, Fig. 1. Fig. 11 is a horizontal sectional view of the plug. Fig. 12 is a transverse sectional view thereof, and Fig. 13 an end view. Fig. 14 is a section on line 14—14, Fig. 1, looking in the direction of the arrow. Fig. 15 is a view of the plug support with the plug removed. Fig. 16 shows the plug support as well as the support for the cord employed in the modification indicated in Figs. 8 and 9.

Referring to the drawings, 1 designates the lamp in its entirety, the same embodying, in addition to the incandescent lamp bulb, a reflector 2 and an inclosing casing 3, which latter is preferably of cylindrical formation and is exteriorly threaded as at 4. The lamp is inclosed by casing 3, and the reflector 2 is over the outer end of the lamp.

5 is the connecting cord which is preferably covered with a coiled protector 6 at its point of entrance into casing 3 in a manner well known in the art, and for the purpose of accommodating this protector when the lamp is not in use, I form in the lamp casing 3 a longitudinally extended chamber 7 open at its outer side and in which the protector may be readily located with its outer portion within the curvature of the casing. This 60 enables the lamp handle, which is shown in the form of an inclosing cover 8 to be secured in place to retain the protector within the chamber. This cover is preferably of 65 cylindrical formation and closed at its outer end, its inner end being interiorly threaded to engage thread 4 of the lamp casing. It will be observed that the casing extends only 70 part of the way over protector 6, but sufficiently far to retain it within the chamber.

10 designates a spool or support for the connecting cord and upon which the latter may be wound when not in use and thus inclosed by the handle or cover 8. This support is shown as extending from a base 12 of the lamp, and in the form of a narrow rod, but it may be differently formed if desired. It extends longitudinally of the axis of the lamp casing within the hollow handle 80 or cover thereof. The cord may be wound around the support, as clearly shown in Fig. 4, and partly outlined in Figs. 1 and 6. The base 12 has a peripheral cut out 13 through which the cord may pass, such cut 85 out being coincident with the lower end of chamber 7.

15 designates the plug to which the free end of cord 5 is connected. This plug is of any suitable insulating material, but is preferably of semi-circular formation, and is equipped with two terminal lugs 16 of known construction. The plug is interiorly hollowed out or formed with chambers to allow cord 5 to be connected to the two 95 terminal lugs, and it is also provided, at its periphery, with a cut-out 16' which extends out through one of the flat sides of the plug so as to enable the cord to be carried at right angles to the terminal lugs. For the purpose of supporting the plug within the lamp, or, more properly speaking, connecting it to the lamp when not in use, I provide two 100 sockets 20 to accommodate terminal lugs 16 of the plug. In Figs. 1, 3 and 4 I have shown these sockets 20 as projecting from a web plate 21 carried by a disk 22 at the

outer end of the cord supporting rod 10, and I have shown such disk 22 as having a peripheral cut out 23 for the passage of the cord, as clearly seen in Fig. 1. In the same figure I have also shown the web plate as having a second disk 24 at its outer end. It is immaterial, however, whether the plug support be located at the outer end of the cord supporting rod 10, since, as shown in Fig. 6, it may be located at the inner end of such rod. Indeed, the rod itself is not an absolutely necessary element since, as clearly shown in Fig. 7, it may be dispensed with, in which event the plug support will depend directly from the lamp base and the outer disk 24^a thereof will be provided with two peripheral cut-outs to accommodate the connecting cord which latter will be bundled within and inclosed by the cylindrical handle or cover 8.

Although I prefer to give the lamp casing and handle a cylindrical formation they may be of substantially elliptical shape as shown in Figs. 8, 9 and 16, and likewise, instead of attaching the handle or cover to the lamp casing by a screw thread the open end of the handle or cover may be split and held in place by tension, as shown in Fig. 8. The form of the cord support 10^a in Fig. 16 is different from that which I preferably employ, but it is manifest that any preferred formation may be adopted.

The advantages of my invention will be apparent from the foregoing. It will be seen that when the lamp is not in use the cord may be wound on its support and inclosed by the hollow handle which forms the cover, or it may be bundled into the latter as indicated in Fig. 7. The plug is held out of the way by being mounted on its support, at right angles to the axis of the lamp casing, at either the outer or inner end of the cord support, and when the lamp is not in use the cord protector 6 is held by the handle or cover within its retaining chamber. Likewise, when the lamp is in use, the cover may be restored to the lamp casing so as to serve as a handle, and inasmuch as this handle or cover does not extend wholly over the protector chamber 7 such protector may project outwardly from the lamp without interference from the handle or cover. When the latter is removed the cord may be readily unwound by revolving the lamp in the hand of the operator and the terminal lugs inserted in suitable sockets, and when the use of the lamp is at an end and the cord wound on its support or placed within the casing the plug will be held out of the way by its support. By giving to the plug a semi-circular formation it allows the handle or cover to be placed in or removed from position without interference therefrom.

Changes may be made without departing from the spirit of my invention.

I claim as my invention:

1. A portable electric lamp comprising a lamp casing, a connecting cord secured thereto, a plug connected by said cord to the lamp, and a hollow handle of substantially the same formation in cross section as the lamp casing to which it is detachably secured for inclosing the cord and plug when the latter are not in use. 70

2. A portable electric lamp comprising a lamp casing, a connecting cord secured thereto, a plug connected by said cord to the lamp, a support for said plug carried by the lamp casing and located at right angles to the axis thereof, and a hollow handle of substantially the same formation in cross section as the lamp casing to which it is detachably secured for inclosing the cord, the 80 plug and the support therefor when the lamp is not in use.

3. A portable electric lamp comprising a lamp casing, a connecting cord secured thereto, and a hollow handle of substantially 90 the same formation in cross section as the lamp casing to which it is detachably secured for inclosing the cord when the lamp is not in use.

4. A portable electric lamp comprising a 95 lamp casing, a connecting cord secured thereto, a support for said cord carried by the lamp casing and arranged longitudinally of the axis thereof, and a hollow handle detachably secured to the lamp cas- 100 ing for inclosing the cord in its support.

5. A portable electric lamp comprising a lamp casing, a connecting cord secured thereto, a support for said cord carried by the lamp casing and arranged longitudinally of 105 the axis thereof, a plug connected by said cord to the lamp, a support for said plug also carried by the lamp casing and ar- ranged at right angles to the axis thereof, and a hollow handle detachably secured to 110 the lamp casing for inclosing the cord, the plug and the support therefor when the lamp is not in use.

6. A portable electric lamp comprising a lamp casing, having a longitudinally ex- 115 tending chamber open at its outer side, a connecting cord designed to fit within said chamber, a base for said lamp having a peripheral cut out to accommodate said cord, and an inclosing cover for projecting in 120 part over said chamber, and for inclosing said cord when the lamp is not in use.

7. A portable electric lamp comprising a lamp casing, having a longitudinally extending chamber open at its outer side, a con- 125 necting cord, a protector thereon designed to fit within said chamber, and an inclosing cover for projecting in part over said cham- ber and for inclosing said cord when the lamp is not in use. 130

8. The combination with the lamp casing having in one side a longitudinally-extended chamber open at its outer side, a base at the end of said casing having a peripheral cut 5 out coincident with said chamber, a connecting cord extending through said casing and designed to fit within said chamber, a cover detachably secured to said lamp casing and designed to extend partly over said 10 chamber for retaining the cord therein when the lamp is not in use, and means for detachably securing said cover.

9. A portable electric lamp comprising a lamp casing, a connecting cord secured thereto, a plug connected by said cord to the lamp, said plug having terminal lugs projecting therefrom, and a support for the plug carried by the lamp casing and arranged at right angles to the axis of the 20 latter, said support comprising a fixed plate having sockets to accommodate said terminal lugs when the lamp is not in use, and a hollow handle for the lamp for concealing said plug and cord.

25 10. A portable electric lamp comprising a cylindrical lamp casing, a connecting cord secured thereto, a plug having terminal lugs to which said cord is connected, said plug being of semi-circular formation, a support 30 for the terminal lugs carried by the lamp, the periphery of the plug when held by said support being within the periphery of the lamp casing, and a cylindrical cover detachably secured to the lamp casing for inclosing 35 the cord and plug when the lamp is not in use.

11. A portable electric lamp comprising a cylindrical lamp casing, a connecting cord secured thereto, a plug having terminal lugs 40 to which said cord is connected, said plug being of semi-circular formation and having a peripheral cut out for the passage of the cord at right angles to the terminal lugs, a support for the latter carried by the lamp,

and a cylindrical cover detachably secured 45 to the lamp casing for concealing the plug and cord when the lamp is not in use.

12. A portable electric lamp comprising a cylindrical lamp casing, a connecting cord secured thereto, a cord support having a 50 disk-like portion, a plug secured to said cord having a semi-circular formation conforming to said disk, a support for said plug adjacent the said disk, and a cylindrical cover detachably secured to the lamp casing for 55 inclosing the cord and plug.

13. A portable electric lamp comprising a cylindrical lamp casing, a connecting cord secured thereto, a plug having terminal lugs to which said cord is connected, said plug 60 being of semi-circular formation and having openings through its curved portion for the passage of the cord and also having a peripheral cut-out through which the cord may pass at right angles to the terminal 65 lugs, a support for the plug, and a cylindrical cover detachably secured to the lamp casing for inclosing the cord and the plug when the lamp is not in use.

14. A portable electric lamp comprising a 70 cylindrical lamp casing, a connecting cord secured thereto, a cord support having a disk-like portion formed with a peripheral cut-out, a plug secured to said cord having a semi-circular formation for conforming to 75 said disk, a support for said plug adjacent to said disk, said cord being designed to pass through said cut-out when the plug is in said support, and a cylindrical cover detachably secured to the lamp casing. 80

In testimony whereof, I have signed this specification in the presence of two subscribing witnesses.
